(57) **CLAIM**

The ornamental design for a right-angle electrical connector housing, as shown and described.

DESCRIPTION

This is related by subject matter to U.S. patent application Ser. No. 29/443,213, filed Jan. 14, 2013 now U.S. Pat. No. D712,841; U.S. patent application Ser. No. 29/443,595, filed Jan. 18, 2013 now U.S. Pat. No. D712,842; and U.S. patent application Ser. No. 29/497,094, filed Jul. 21, 2014 now U.S. Pat. No. D738,313.

FIG. 1 is a top, right, front perspective view of a right-angle electrical connector showing our new design;

FIG. 2 is a bottom, left, rear perspective view thereof;

FIG. 3 is another top, right, front perspective view thereof;

FIG. 4 is a bottom, left, front perspective view thereof;

FIG. 5 is a top, left, rear perspective view thereof;

FIG. 6 is a bottom, right, rear perspective view thereof;

FIG. 7 is a front elevation view thereof;

FIG. 8 is a rear elevation view thereof;

FIG. 9 is a top plan view thereof;

FIG. 10 is a bottom plan view thereof;

FIG. 11 is a left side elevation view thereof; and,

FIG. 12 is a right side elevation view thereof.

The broken line portion of the figure drawings is included to show unclaimed subject matter only for the purpose of illustrating environment and forms no part of the claimed design. The dash-dot line in the drawing represents the boundary of the claimed design.

In a preferred embodiment, the nature of this product is an electrical component that can take the form of a right-angle electrical connector housing.
